UNITED STATES PATENT OFFICE.

WALTER V. HART, OF JACKSONVILLE, FLORIDA, ASSIGNOR TO SIMON F. WILLIAMS,
OF JACKSONVILLE, FLORIDA.

GATE.

1,426,474.

Specification of Letters Patent. Patented Aug. 22, 1922.

Application filed September 25, 1920, Serial No. 412,812. Renewed July 13, 1922. Serial No. 574,783.

To all whom it may concern:

Be it known that I, WALTER V. HART, a citizen of the United States, residing at Jacksonville, in the county of Duval and 5 State of Florida, have invented a new and useful Gate, of which the following is a specification.

It is the object of this invention to provide novel means for imparting swinging movement to a gate mounted to move in a vertical plane, the construction being such 10 that the gate may be lifted out of engagement with a keeper which tends to hold the gate in a closed position.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the accompanying drawings:

30 Figure 1 shows in side elevation, a device constructed in accordance with the invention, parts being broken away and the gate being closed; Figure 2 is a side elevation wherein the gate is shown open; Figure 3 is an end elevation; Figure 4 is a section on the line 4—4 of Figure 3; Figure 5 is a section on the line 5—5 of Figure 3; Figure 6 is a fragmental elevation showing a portion of the gate, parts being broken away; and Figure 7 is a section on the line 7—7 of Figure 6.

The numeral 1 denotes a support which may consist of a pair of parallel posts. The numeral 2 designates the frame of a gate. 45 A reinforcing member 3 is secured to the lower inner corner of the gate frame 2. Plates 5 lie against the outer surface of the reinforcing member 3 and are connected at 7 to angular arms 6. The arms 6 are united by a securing element 8 having movement in 50 the gate, a spacer 80 being carried by the securing element 8 and being located between the arms 6 as clearly shown in Figure 5. The plates 5 are mounted on a bolt 9 carried by the reinforcing member 3. The

plates 5 and the arms 6 constitute a lever, fulcrumed on the bolt 9. A pivot bolt 10 is received in openings 11 in the plates 5 and fits closely therein. See Figure 7. The pivot bolt 10 is mounted in the posts 1. The 60 reinforcing member 3 is provided with openings 12 through which the pivot bolt 10 passes. The pivot bolt 10 serves to support the gate frame for swinging movement in a vertical plane, but the opening 12 in the reinforcing member 3 is large enough so that the gate can have some movement with respect to the pivot bolt 10. The utility of the detail last above alluded to will be made manifest hereinafter. Spacers 14 are interposed between the plates 5 and the posts 1. See Figure 5. An anchor 15 is secured at 16 to the lower portion of the gate frame 2. Retractile springs 17 are connected at their lower ends to the anchor 15, the upper ends 75 of the springs being connected to the arms 6.

The lower ends of links 18 are pivoted at 19 to the arms 6 at a point adjacent to the plates 5. The upper ends of the links 18 are pivotally mounted at 20 in the outer 80 ends of radius arms 21 pivoted at 22 for vertical swinging movement to the posts 1. Links 23 are provided, the lower ends of the links 23 being pivoted at 24 to the radius arms 21, intermediate the ends of the radius 85 arms. The upper ends of the links 23 are pivoted at 25 in the inner ends of oppositely extended operating levers 26 fulcrumed at 27 on brackets 28 carried by the posts 1, the brackets being supported by braces 29. A 90 transverse latch 30 is secured at 31 to the inner end of the gate frame 2. The latch 30 is adapted to be received in seats 32 formed in the upper edges of keepers 33 secured to the posts 1. The keepers 33 have inclined 95 edges 34.

In practical operation, when either of the levers 26 is swung downwardly at its outer end, the corresponding link 23 swings the radius arm 21 upwardly, and motion is imparted to the lever 5—6 by way of the link 18, the lever tilting on its fulcrum 9, and the springs 17 being put under tension, the springs serving as cushioning elements. Passing to Figure 6, and noting that the 105 plates 5 of the levers are mounted on the pivot element 10, the first result produced is that the gate is raised slightly, the fulcrum point 9 moving upwardly. The gate can rise slightly, because the diameter of 110

the opening 12 is considerably greater than the diameter of the pivot bolt 10. The rising movement of the gate, above alluded to, disengages the latch 30 from the keepers 33. 5 Next, the gate is swung backward with the bolt 10 as a pivot, the gate swinging into the vertical, open position shown in Figure 2. The gate may be closed by pulling downwardly upon either of the levers 26 at its 10 outer end, and, as the gate moves toward a closed position, the latch 30 rides along the beveled or inclined edges 34 of the keepers 33 and is received in the seats 32. When the latch 30 is received in the seats 32 of the 15 keepers 33, the gate cannot be opened by a swinging movement, but must be lifted vertically from a point adjacent to its inner end, this lifting force being applied, as aforesaid, through the lever 5—6, by way of 20 the springs 17. Owing to the construction and the operation last above alluded to, the gate cannot be swung upwardly by swine or other small animals which might tend to nose under the gate, or by cattle hooking 25 into the gate.

Having thus described the invention, what is claimed is:—

1. In a device of the class described, a support; a pivot element carried by the support; a gate mounted at its lower inner corner to swing vertically on the pivot element; a lever fulcrumed on the pivot element; an operating member connected to the lever and constituting means for swinging the gate on the pivot element; and a retractile spring connected with the lever and with the gate and serving as a cushioning

means at the inception of the swinging of the gate by the operating member.

2. In a device of the class described, a support; a pivot element carried thereby; a gate mounted on the pivot element and having a limited amount of lost motion thereon; a lever fulcrumed on the gate and mounted to swing on the pivot element; a spring connecting the lever with the gate; an operating means; and mechanism for connecting the operating means with the lever.

3. In a device of the class described, a support; a pivot element carried by the support; a gate mounted to swing vertically on the pivot element and having a limited amount of lost motion on the pivot element; a keeper on the support; a latch on the gate and engaging the keeper; and means for lifting the gate vertically, to disengage the latch from the keeper, and for swinging the gate to an open position on the pivot element.

4. A device of the class described constructed as set forth in claim 3, and further characterized by the fact that the last specified means embodies a lever mounted on the pivot element and fulcrumed on the gate, and mechanism under the control of an operator for actuating the lever.

In testimony that I claim the foregoing as my own, I have hereto affixed my signature in the presence of two witnesses.

WALTER V. HART.
